HIGH-FREQUENCY SIGNALING SYSTEM

Harold A. Wheeler, Great Neck, Long Island,
N. Y., assignor to Hazeltine Corporation, a
corporation of Delaware

Application May 22, 1935, Serial No. 22,699

18 Claims. (Cl. 250—20)

This invention relates to high-frequency signaling systems and particularly to systems of this character having a plurality of circuits which are simultaneously tunable to different frequencies and over different frequency ranges, as, for instance, tunable selector coupling circuits for antennas and/or radio-frequency amplifiers and tunable oscillator circuits, such as are generally employed in superheterodyne radio receivers.

10 This application is a continuation-in-part of application, Serial No. 691,927, filed October 3, 1933, Patent No. 2,050,679, August 11, 1936, for Radio receiver.

More particularly, the invention is directed to maintaining constant the frequency difference of circuits as above described by the provision of improved aligning means in connection with one or more of the circuits.

Various arrangements have heretofore been devised in attempts to provide correct alignment of circuits such as those mentioned, or, in other words, to maintain constant the frequency difference between these circuits over their respective ranges. According to one approved and widely employed practice, there are provided tuning condensers having a constant ratio of capacitances, that is, having plates of similar size and shape which are all similarly adjustable at the same rate, and unicontrol means therefor, for tuning, 20 or changing the resonant frequency of, a selector circuit or circuits simultaneously with that of an oscillator circuit, over different frequency ranges and with an approximately constant frequency difference therebetween. With such an arrangement, the respective resonant frequencies of the circuits vary in accordance with characteristic curves of frequency versus condenser adjustment which are spaced in the frequency scale one above the other, the higher one usually being that of 30 the oscillator circuit. These curves, however, are not exactly parallel to each other, as would, of course, be the case if the frequency difference was exactly constant over the entire ranges. In other words, the frequency difference varies over 40 the ranges of the circuits and the frequency of the circuit having the higher curve is ordinarily too high at the upper end of the range and too low at the lower end thereof.

The provision in the last-named circuit, as in 50 usual practice, of series and parallel padding or aligning condensers, or their equivalents, and the adjustment of the main inductance thereof changes the frequency-condenser adjustment curve of this circuit. The resulting curve, while 55 not exactly coinciding with the curve of ideal

alignment, improves the alignment at the lower and upper ends of the frequency range and passes through the ideal curve at three points, to wit: a central point wherein the proper alignment is effected by the adjustment of the main inductance of the circuit; a point near the lower frequency end where alignment is corrected by the provision of the series padding condenser; and a point near the upper frequency end where the alignment is corrected by the provision of the 10 parallel padding condenser. The remaining frequency errors are evidenced by the departure from the ideal of portions of the curve at the opposite sides of the upper and lower points of alignment mentioned, which portions indicate 15 that the tuning frequency above the points is then too low and below the points is too high. It will thus be seen that, at the intersection points of the actual curve with the ideal curve, the frequency difference is at a desired normal value 20 and that at all other frequencies within the respective frequency ranges of the circuits to be aligned the frequency difference departs from this desired normal value in one direction or the other. The present invention, however, serves 25 to maintain the frequency difference of the circuits more nearly constant over their respective tuning ranges, or, in other words, reduces the remaining alignment errors by increasing the 30 number of frequencies at which the frequency difference is at the desired normal value and decreasing the departure of the frequency difference from this normal value at other frequencies within the ranges.

The primary object, therefore, of this invention is to provide, in a system embodying circuits simultaneously tunable to different frequencies and over different frequency ranges, novel and improved means, effectively connected in at least one of the circuits, for maintaining the frequency 35 difference between the circuits substantially constant over their respective tuning ranges.

Further objects of, and advantages achieved by, the invention, including the provision of aligning means for tunable circuits of the character described which are characterized by simplicity of construction and efficiency of operation with improved results, will be apparent from the following descriptions of approved embodiments 40 of the invention.

In accordance with the present invention, there are provided the usual alignment capacitances effectively in series and in parallel, respectively, with the tuning condenser of a particular circuit 45 to be aligned with another circuit or other cir- 50 55

cuits of the same system, such as above mentioned. The tuning condensers of the circuits are arranged for unictral and have a constant ratio of capacitances, thereby to maintain the frequency difference of the circuits approximately constant. In addition to these aligning capacitances, auxiliary means is connected effectively in series in this circuit for procuring a more nearly constant frequency difference.

- 10 The auxiliary means comprises reactance means, which may be either a capacitance or an inductance or both, connected in circuit with a resistance. In certain forms of the invention the auxiliary means is connected directly in series 15 in the tunable circuit that is to be aligned, and in other forms it constitutes a separate circuit and is reactively coupled to the tunable circuit. The reactance of the auxiliary means is variable with frequency, the elements thereof being proportioned to effect increases and decreases in the 20 effective reactance of the tunable circuit at the proper frequencies more nearly to approximate a constant frequency difference between the several circuits. The resistance varies the effective 25 reactance of the auxiliary circuit gradually with frequency at the rate necessary to change the reactance of the tunable circuit, as required.

A better understanding of the present invention will be had from the following detailed 30 description, taken in connection with the accompanying drawings, and its scope will be apparent from the appended claims.

In the accompanying drawings, Fig. 1 is a circuit diagram, partially schematic, of a complete 35 superheterodyne radio receiver including radio-frequency amplifier circuits and an oscillator circuit with the present invention applied in connection therewith; Fig. 2 is a circuit diagram of another embodiment of the invention applied in 40 connection with a receiver having a tunable antenna coupling circuit and an oscillator circuit; Figs. 3-7 are curves illustrating the principles of operation of the present invention; Figs. 8 and 9 are fragmentary circuit diagrams illustrating 45 other embodiments of the invention; and Fig. 10 is a curve illustrating the operating characteristics of the circuit of Fig. 8.

Referring particularly to Fig. 1 of the drawings, the receiver there illustrated includes an 50 antenna 10 connected to ground 11 through a primary winding 12 of a radio-frequency transformer, a secondary winding 13 of which is tuned by an adjustable condenser 14 providing a tunable radio-frequency selector circuit 15. The 55 circuit 15 is connected at one point with the grid of an amplifier tube 16, of the conventional pentode type, and at another point, through ground and a cathode biasing circuit, to the cathode of this tube. The output circuit of the tube 16 extends 60 from the anode of the tube through a primary winding 17 of a second radio-frequency transformer and through a source of B voltage and ground to the cathode of the tube. The secondary winding 18 of the last-mentioned 65 transformer is tuned by an adjustable condenser 19 providing a second tunable selector circuit 20. Padding condensers 15a and 20a are connected in the circuits 15 and 20, respectively, in parallel 70 with the condensers 14 and 19 of these circuits to correct slight differences in minimum circuit capacitances in the usual manner. The circuit 75 20 is connected at one point to a control grid of an oscillator-modulator tube 21 and at another point, through ground and a cathode biasing circuit, to the cathode of this tube. The

oscillator-modulator system is of the type described in U. S. Letters Patent 1,958,027, to which patent reference may be had for a detailed description of the characteristics and principles of operation of this system. This system includes 5 an oscillation circuit 22, embodying an inductance 23 and an adjustable tuning condenser 24, the latter being mechanically connected for unictral with the condensers 14 and 19, as indicated by the broken lines U. The oscillation circuit 22 is included directly in the oscillator grid circuit of the tube 21 and is coupled to the oscillator anode of this tube through a winding 23a, coupled to or forming a continuation of the inductance 23. A blocking condenser 23b is included in the oscillator anode circuit, and a choke coil 23c is included between the oscillator anode and its voltage source +B.

The signal output or anode circuit of the tube 21 is coupled through a double-tuned intermediate-frequency transformer 25 to an intermediate-frequency amplifier which is, in turn, connected in cascade with a detector, an audio-frequency amplifier and a sound reproducer, or loudspeaker L. The parts following the transformer 25, 25 being of conventional type, are indicated schematically in the drawings. Suitable resistors, bypassing condensers and similar elements are indicated in the circuits where such elements are needed to improve the operation of the receiver, 30 in accordance with conventional practice.

In accordance with the present invention there are provided the usual aligning condensers 26 and 27, connected, respectively, in series and in parallel with the tuning condenser 24 of the 35 oscillation circuit 22; and in addition thereto auxiliary aligning means are provided. The auxiliary means comprises a circuit 28 which includes an inductance 29, a condenser 30 and a resistor 31, all connected in parallel. The inductance 29 is inductively coupled to the inductance 23 thereby to connect the parallel circuit 28 effectively in series in the oscillation circuit.

Neglecting for the present the particular operation and effect of the auxiliary aligning means 45 of the present invention, which will be herein-after described in detail, the above-described system constitutes in general a conventional type of superheterodyne radio receiver the operation of which is well known to those skilled in 50 the art, so that a detailed description thereof is deemed unnecessary. Briefly, however, the radio-frequency signals intercepted by the antenna 10 are selected by the tunable selector circuit 55 15, amplified by the tube 16, subjected to a second selection in the tunable circuit 20 and converted by the oscillator-modulator tube 21 into an intermediate frequency, which is the difference in frequencies of the oscillation circuit 22 and the selected signal. The intermediate frequency thus produced, modulated by audio-frequency signals, is amplified in the intermediate-frequency amplifier and then rectified or detected to derive the audio-frequency component, which is successively amplified, and reproduced in the loudspeaker.

The circuit 22, as in usual practice, is so designed as to be tunable at different frequencies from, and over a different frequency range than that of, the circuits 15 and 20. More particularly, 70 the inductance 23 is smaller than the inductances 13 and 18 (which are substantially equal) while the condensers 14, 19 and 24 have a constant ratio of capacitances, that is, their plates are of similar size and shape, and they are simultane- 75

ously adjustable at the same rate by the unicontrol means U. Thus, the range of frequencies of the circuit 22 is higher than the range of the other two circuits and the particular frequencies to which the circuit 22 is tuned are higher than the corresponding frequencies to which the other two circuits are tuned. The range of the circuits 15 and 20 is preferably from 550 to 1500 kilocycles, that is, the broadcast band, while the range of the oscillation circuit 22 is equal to the range of the circuits 15 and 20 plus the intermediate frequency. Assuming an intermediate frequency of 112 kilocycles, for example, the range of the oscillation circuit will be from 662 to 1612 kilocycles. For correct alignment of the circuits, the frequency difference between the oscillation circuit and the circuits 15 and 20 should be maintained constant over their respective ranges.

Referring now more particularly to the operation of the circuit 28, as applied in connection with the oscillation circuit 22, the manner in which this circuit is aligned in accordance with this invention will be described with reference to the characteristic curves shown in Figs. 3 to 7.

In Fig. 3 characteristic curves of resonant frequency versus condenser setting for the circuits in question are shown. Condenser settings, from maximum to minimum, are represented by the abscissae, while the ordinates represent frequencies, for example, from 550 to 1612 kilocycles. The curve 32 indicates the resonant frequencies of the circuits 15 and 20 for various settings of their respective tuning condensers, while the desired or ideal curve of frequency versus condenser setting for the oscillation circuit 22 is indicated by the dotted line 33, which, of course, is parallel to the curve 32, indicating a constant frequency difference over the entire ranges of the circuits.

With only the inductance 23 and condenser 24 included in circuit 22, its frequency condenser setting curve would be as indicated by the curve 34 of Fig. 3, which intersects the curve 33 only at the point 35, showing that the frequency difference is at the desired normal value and the alignment of the circuits is correct only at this point. The alignment at point 35 is effected by proper proportioning of the inductance 23. At other frequencies the circuits are not aligned; that is, the frequencies of the circuit 22 above this point are too high while below this point they are too low. The series padding condenser 26, however, serves to correct the lower portion 55 of the curve 34, as indicated by the curve 36, and the parallel trimmer condenser 27 serves to correct the upper portion of the curve 34, as indicated by the curve 37, thus improving the alignment at both ends of the frequency range. This is according to conventional practice and a detailed explanation of the theory thereof is unnecessary. It is apparent from the curves 36 and 37, however, that frequency errors are still present, or, in other words, the frequency difference 60 of the oscillator circuit and the selector circuits is still not exactly constant. While the curves 36 and 37 intersect the ideal curve 33 at the points 38 and 39, respectively, just above these points, the oscillator frequencies are too low and just below these points they are too high.

The auxiliary aligning circuit 28 serves to correct these remaining frequency errors, thus maintaining the frequency difference between the circuits more nearly constant over their respective tuning ranges. Either a single circuit 28 may be

employed, as shown in the drawings, which circuit will function mainly at one of the ends of the frequency range, or, if desired, two such circuits may be employed, one for each end thereof.

In the embodiment illustrated in Fig. 1 the inductance 29 and condenser 30 are proportioned to tune the circuit 28 to the frequency indicated at the point 39, where the curve 37 intersects the curve 33, or, where the frequency difference is at the desired normal value. As thus proportioned, the circuit 28 has an effect which is equivalent to adding inductance in the oscillator circuit at frequencies below the point 39 and subtracting inductance at frequencies above this point, with the resultant effect of increasing and decreasing, respectively, the frequencies of the oscillator circuit above and below this point. The resistance 31, as heretofore mentioned, broadens the resonance characteristic of the circuit 28 and effects a more gradual variation of the reactance 20 of the oscillator circuit. The size of the resistance is so limited that the added impedance reflected by the auxiliary means into the circuit 22 will not seriously reduce the amplitude of the oscillations of the circuit. 25

Figs. 4-7 represent curves of frequency error or misalignment of the oscillator circuit over its tuning range. In Fig. 4, the curve 41 indicates the best alignment obtainable by employing only the aligning condensers 26 and 27, the portions 30 of the curve 41 above and below the zero axis indicating positive and negative alignment errors respectively. The point 42 corresponds to the point 39 of Fig. 3. The curve 43 indicates the change in oscillator frequencies which is produced by the inclusion of the circuit 28, tuned to the frequency indicated at 39. The curve 44 of Fig. 5 is the resultant alignment curve representing the sum of the curves 41 and 43. Having obtained this curve 44, the series padding condenser 40 26 is then readjusted to increase the frequencies at the lower end of the range, and a resultant alignment is thus obtained such as is indicated by the curve 45 of Fig. 6. The main inductance 23 is then readjusted, that is, reduced the necessary 45 amount, and a resultant alignment is thereby obtained such as is indicated by the curve 46 of Fig. 7. It is thus apparent that by adding the auxiliary circuit, proportioned as described, the frequency difference is made more nearly constant, 50 and ideal or exact alignment is closely approximated.

In Fig. 2 there is illustrated another form of the invention, applied in connection with a receiver somewhat similar to that shown in Fig. 1, 55 corresponding elements being indicated by the same reference numerals. Here, however, a tunable coupling circuit 50 is substituted for the radio-frequency selector circuits 15 and 20 of Fig. 1, the antenna circuit 10-11 being directly 60 connected by the circuit 50 to the oscillator-modulator tube 21. The parts of the system following the transformer 25 are omitted from Fig. 2, but they will be understood to be the same as those indicated in Fig. 1. 65

The coupling circuit 50 is a parallel resonant circuit the arms of which comprise, respectively, a tuning condenser 51 and a coupling condenser 52 connected in series, and a fixed inductance 53. The antenna circuit is connected directly across 70 the coupling condenser 52 and output terminals of the circuit are connected across the tuning condenser 51, and connect the circuit 50 to the signal input circuit of the tube 21. If desired, padding or aligning condensers 54 and 55 may be con- 75

nected in parallel with the tuning condenser 51 and the coupling condenser 52, respectively. A resistor 58 serves to connect the lower terminal of the inductance 53 with ground to provide a direct current path for the signal control grid of tube 21, thus to determine its potential and to permit a variable bias to be applied for automatic volume control or other purposes. This particular antenna coupling circuit permits more accurate alignment with relatively higher gain than is ordinarily possible with such circuits. As the coupling circuit per se forms no part of this invention, a detailed description of its characteristics and operation will not be here necessary, such circuit being disclosed and broadly claimed in the copending application of Daniel E. Harnett, Serial No. 18,362, filed April 26, 1935, for improvements in high-frequency coupling circuits.

The oscillator-modulator system of this embodiment and the succeeding parts of the system, as well as the general operation of the receiver, are the same as in the embodiment shown in Fig. 1, and further details in these respects are, therefore, unnecessary. The oscillation circuit 22' includes an inductance 23', a tuning condenser 24', and aligning condensers 26' and 27' similar to the corresponding elements of the circuit 22. An auxiliary alignment circuit 28' is provided in this embodiment, which includes an inductance 29', a condenser 30', and a resistor 31', all connected in parallel. In this embodiment, the circuit 28' is directly connected in series in the oscillation circuit 22'. The operation and effects of the auxiliary alignment circuit 28' are substantially the same as those of the auxiliary alignment circuit 28 of Fig. 1.

While my invention is in no wise limited to any specific circuit design or constants, eminently satisfactory results were obtained in a superheterodyne receiver embodying the present invention and using substantially the circuit arrangement illustrated in Fig. 2. In this receiver the circuits 22', 28', and 50 had the following constants:

Circuit 22'-1010-1960 kilocycles

Inductance 23'	microhenries	163
Condenser 24'	micro-microfarads	15-420
Condenser 27'	micro-microfarads	10
Condenser 26'	micro-microfarads	500

Circuit 28'

Condenser 30'	micro-microfarads	850
Resistance 31'	ohms	250
Inductance 29'	microhenries	8

Circuit 50-550-1500 kilocycles

Condenser 51	micro-microfarads	15-420
Condenser 52	micro-microfarads	15-420
Inductance 53	microhenries	390
Condenser 55	micro-microfarads	10
Resistance 58	ohms	500,000
Condenser 54	micro-microfarads	210

In Fig. 8 there is illustrated another embodiment of the invention, applied in connection with an oscillator-modulator system, comprising separate modulator and oscillator tubes 60 and 61, respectively. This embodiment is shown in Fig. 1, and described with reference to Figs. 1 and 5 of the drawings of the above mentioned application, Serial No. 691,927, Patent No. 2,050,679. The present application thus constitutes a continuation-in-part of said copending application. While only the oscillator-modulator system is shown in Fig. 8, it is, excepting for the application of the

present invention in connection therewith, of a conventional design and its operation and manner of connection in a receiver provided with unicontrol tuning means for the several tunable circuits thereof, will be readily understood by those skilled in the art, rendering a detailed description in these respects unnecessary in this application.

The system shown in Fig. 8 includes an oscillation circuit 67 comprising a fixed inductance 191, an adjustable tuning condenser 62, which is mechanically connected for unicontrol with the tuning condensers of other tunable circuits of the receiver (not shown), and a series-aligning condenser 190. The equivalent of an additional parallel-aligning condenser, as indicated at 63, may be provided by properly proportioning the condenser 62 to increase its capacity the necessary amount. The oscillation circuit 67 is included in the oscillator grid circuit of the tube 61 and is coupled to the anode of this tube through a winding 64, coupled to, or forming a continuation of, the inductance 191. A blocking condenser 64a is included in the oscillator anode circuit and an isolating resistance 64b is included between the oscillator anode and its voltage source +B. The inductance 191 is also coupled to a winding 65 serially included in the cathode-to-ground connection of the modulator tube 60, whereby the oscillations are fed from the circuit 67 to the tube 60.

The auxiliary aligning means (supplementing the series and parallel aligning capacitances) in this embodiment of the invention constitutes resistors 68 and 69 which may be connected across the windings 65 and 64, respectively, fairly closely coupled to the oscillation circuit 67. These coils thus serve their first-mentioned respective purposes, of coupling the circuit 67 to the tubes 60 and 61, and also constitute reactances connected in parallel with resistances to provide auxiliary aligning means in accordance with this invention. Each of the auxiliary aligning means functions in substantially the same manner as the auxiliary aligning means shown in Figs. 1 and 2, as hereinabove described; that is, they effectively change the inductance of the tuned oscillator circuit at the frequencies where the circuit is misaligned, so as to correct the alignment errors. The resulting curve, illustrating frequency error as a function of oscillator tuning frequency, is shown by curve 131 of Fig. 10, the alignment curve obtaining when the auxiliary means is omitted being shown at 130. It will be seen from a comparison of the two curves that the addition of the auxiliary impedance means substantially lessens the alignment error at all frequencies within the band considered. The auxiliary alignment means of this embodiment is most effective at the high-frequency end of the tuning range.

By way of example only, it may be stated that satisfactory results were obtained from a receiver constructed similarly to the receiver described in my said copending application, with the circuit 67 designed as follows:

Circuit 67-662-1612 kilocycles

Inductance 191	microhenries	249
Condenser 62	microfarads	15-370
Condenser 190	micro-microfarads	1500
Inductance 64	microhenries	63
Inductance 65	microhenries	25
Resistor 69	ohms	5000
Resistor 68	ohms	500
(R. F. circuits)	kilocycles	550-1500

It will be understood that the circuit 67 and the other tunable circuits with which it is to be aligned will have tuning condensers which have a constant ratio of capacitances so that proper alignment thereof may be readily obtained by aligning them at one point, as by adjustment of their respective inductances.

In Fig. 9 there is illustrated another embodiment of the invention, as embodied in an oscillation circuit 70 which includes an inductance 71, a tuning condenser 72, and series and parallel aligning condensers 73 and 74, respectively, in the usual manner. While only the circuit 70 and its immediate connections are shown, it will be understood that this circuit may be substituted for either of the circuits 22 or 22', respectively, of the systems shown in Figs. 1 and 2, it being only necessary to connect the terminals 75—76, shown in Fig. 9, to the respective terminals indicated at 75'—76' in Fig. 1 or Fig. 2. The condenser 72 will be mechanically connected to the other tuning condenser or condensers of the system, as in the embodiments of Figs. 1 and 2. In this embodiment, the auxiliary aligning means of this invention is provided by the condenser 73 and the resistor 77 connected across this condenser and thus providing the parallel circuit 78, which circuit is connected directly in series in the oscillation circuit 70. The condenser 73, by proper adjustment of its capacity, serves as both the usual series aligning condenser and the aligning condenser of the auxiliary means. The operation of this embodiment of the invention is substantially the same as that of the other embodiments, the auxiliary aligning circuit serving effectively to change the reactance of the circuit 70 to modify the characteristic of the circuit over those portions of the range where the alignment errors occur, and thus to maintain the frequency difference more nearly constant.

While various forms of the invention have been described above in connection with oscillation circuits, it will, of course, be understood that the alignment means may be equally well applied to a signal selector circuit or to any one or more tunable circuits which it is desired to align with another or other circuits, in systems such as have been described, in order to maintain the frequency difference between the circuits more nearly constant.

Furthermore, while there has been described what are considered at present to be the preferred embodiments of this invention, it will be obvious to those skilled in the art that various changes and modifications may be made without departing from the invention, and it is therefore aimed in the appended claims to cover all such changes and modifications as fall within the true spirit and scope of this invention.

60 What is claimed is:

1. In a high-frequency signaling system, a pair of circuits tunable to different frequencies and over different frequency ranges, means for simultaneously tuning said circuits over said frequency ranges, reactance means included in one of said circuits for maintaining the frequency difference of said circuits approximately constant over their respective frequency ranges, and reactance and resistance means connected in parallel and effectively connected in circuit with said last-named tunable circuit and proportioned substantially to maintain said frequency difference more nearly constant.

2. In a high-frequency signaling system, a pair of tunable circuits each including an inductance

and an adjustable condenser, said condensers being connected for unicontrol adjustment and having a constant ratio of capacitances whereby the resonant frequencies of said circuits may be varied over different ranges of frequencies with a frequency difference therebetween, reactance means included in one of said circuits for maintaining the frequency difference of said circuits approximately constant over their respective frequency ranges, and reactance and resistance means connected in parallel and effectively connected in circuit with said last-named tunable circuit and proportioned substantially to maintain said frequency difference more nearly constant.

3. In a high-frequency signaling system, a pair of circuits tunable to different frequencies and over different frequency ranges, means for simultaneously tuning said circuits over said frequency ranges, means included in one of said circuits for maintaining the frequency difference of said circuits approximately constant over their respective frequency ranges, comprising condensers included, respectively, in parallel and series with said tuning condenser of said last-named tunable circuit, and auxiliary impedance means effectively connected in circuit with said last-named tunable circuit and proportioned substantially to maintain said frequency difference more nearly constant.

4. In a high-frequency signaling system, a pair of tunable circuits each including an inductance and an adjustable condenser, said condensers being connected for unicontrol adjustment and having a constant ratio of capacitances whereby the resonant frequencies of said circuits may be varied over different ranges of frequencies with a frequency difference therebetween, means included in one of said circuits for maintaining said frequency difference approximately constant over their respective frequency ranges comprising condensers included, respectively, in parallel and series with said tuning condenser of said last-named tunable circuit, and auxiliary means effectively connected in circuit in said last-named tunable circuit and proportioned substantially to maintain said frequency difference more nearly constant over a portion of said frequency ranges including a reactive element and a resistance connected in parallel therewith.

5. In a high-frequency signaling system, a pair of circuits tunable to different frequencies and over different frequency ranges, means for simultaneously tuning said circuits over said frequency ranges, reactance means included in one of said circuits for maintaining the frequency difference of said circuits approximately constant over their respective frequency ranges, and a condenser and a resistance connected in parallel and effectively connected in circuit with said last-named tunable circuit and proportioned substantially to maintain said frequency difference more nearly constant.

6. In a high-frequency signaling system, a pair of circuits tunable to different frequencies and over different frequency ranges, means for simultaneously tuning said circuits over said frequency ranges, reactance means included in one of said circuits for maintaining the frequency difference of said circuits approximately constant over their respective frequency ranges, and an inductance and a resistance connected in parallel and effectively connected in circuit with said last-named tunable circuit and proportioned substantially to maintain said frequency difference more nearly constant.

- maintain said frequency difference more nearly constant.
7. In a high-frequency signaling system, a pair of circuits tunable to different frequencies and over different frequency ranges, means for simultaneously tuning said circuits over said frequency ranges, reactance means included in one of said circuits for maintaining the frequency difference of said circuits approximately constant over their respective frequency ranges, and auxiliary means including an inductance, a condenser and a resistance connected in parallel, said auxiliary means being effectively connected in circuit with said last-named tunable circuit and having its elements proportioned substantially to maintain said frequency difference more nearly constant.
8. In a high-frequency signaling system, a pair of tunable circuits each including an inductance and an adjustable condenser, said condensers being connected for unicontrol adjustment and having a constant ratio of capacitances whereby the resonant frequencies of said circuits may be varied over different ranges of frequencies with a frequency difference therebetween, means included in one of said circuits for maintaining the frequency difference of said circuits approximately constant over their respective frequency ranges, and auxiliary means including an inductance, a condenser and a resistance, connected in parallel, the inductance of said auxiliary means being coupled to the inductance of the last-named tunable circuit and the elements of said auxiliary means being proportioned substantially to maintain said frequency difference more nearly constant.
9. In a superheterodyne radio receiver, a signal-selector circuit and an oscillation circuit tunable to different frequencies and over different frequency ranges, means for simultaneously tuning said circuits over said frequency ranges, reactance means included in one of said circuits for maintaining the frequency difference of said circuits approximately constant over their respective frequency ranges, and resistance and reactance means connected in parallel and effectively connected in circuit with said last-named tunable circuit and proportioned substantially to maintain said frequency difference more nearly constant.
10. In a superheterodyne radio receiver, a signal-selector circuit and an oscillation circuit, tunable to different frequencies and over different frequency ranges, means for simultaneously tuning said circuits over said frequency ranges, reactance means included in said oscillation circuit for maintaining the frequency difference of said circuits approximately constant over their respective frequency ranges, and resistance and reactance means connected in parallel and effectively connected in circuit with said oscillation circuit and proportioned substantially to maintain said frequency difference more nearly constant.
11. In a superheterodyne radio receiver, a signal-selector circuit and an oscillation circuit, each including an inductance and an adjustable condenser, said condensers being connected for unicontrol and having a constant ratio of capacitances whereby the frequencies of said circuits may be varied over different ranges of frequencies with a frequency difference therebetween, means included in one of said circuits for maintaining said frequency difference of said circuits approximately constant over their respective frequency ranges, comprising condensers included, respectively, in parallel and series with said tuning con-
- denser of said last-named tunable circuit, and auxiliary means effectively connected in circuit in said last-named tunable circuit and proportioned substantially to maintain said frequency difference more nearly constant over a portion of said frequency ranges, said auxiliary means including a reactive element and a resistance connected in parallel therewith.
12. In a superheterodyne radio receiver, a signal-selector circuit and an oscillation circuit each including an inductance and an adjustable condenser, said condensers being connected for unicontrol and having a constant ratio of capacitances whereby the frequencies of said circuits may be varied over different ranges of frequencies with a frequency difference therebetween, means included in one of said circuits for maintaining said frequency difference of said circuits approximately constant over their respective frequency ranges, said means comprising condensers included, respectively, in parallel and series with said tuning condenser of said last-named circuit, and auxiliary means effectively connected in series in said last-named tunable circuit and proportioned to maintain said frequency difference more nearly constant, said auxiliary means including an inductance, a condenser and a resistance connected in parallel, said auxiliary inductance and condenser being tuned to a frequency at one end of one of said ranges.
13. In a superheterodyne receiver with unicontrol tuning, the arrangement comprising a selector to be tuned to any signal frequency in a given tuning range, an oscillator circuit to be simultaneously tuned to a different frequency, several reactance elements connected in the oscillator circuit and adjusted to maintain the frequency difference approximately uniform, and parallel connected resistance and reactance in the oscillator circuit, adjusted to substantially improve the uniformity of the frequency difference.
14. In a superheterodyne receiver with unicontrol tuning, the arrangement comprising a selector to be tuned to any signal frequency in a given tuning range, an oscillator circuit to be simultaneously tuned to a different frequency, several reactance elements connected in the oscillator circuit and adjusted to maintain the frequency difference approximately uniform, and parallel connected resistance and inductance coupled to one of said reactance elements, adjusted to substantially improve the uniformity of the frequency difference at the higher frequencies in the oscillator tuning range.
15. In a high-frequency signaling system, a pair of circuits, adjustable reactance means for simultaneously tuning said circuits to different resonant frequencies and over different frequency ranges whereby a frequency difference exists between the resonant frequencies of said circuits, means connected in one of said circuits for maintaining said frequency difference approximately constant as the tuning of said circuits is varied to vary said resonant frequencies over their respective frequency ranges, and additional means comprising an impedance network including an impedance element of a type different from said tuning reactance means and effectively connected in said last-named circuit for maintaining said frequency difference more nearly constant.
16. In a high-frequency signaling system, a pair of circuits tunable to different frequencies and over different frequency ranges, means for simultaneously tuning said circuits over said

- ranges, reactance means included in one of said circuits for maintaining the frequency difference of said circuits approximately constant over their respective tuning ranges, and additional means comprising a third circuit resonant at a frequency at one end of the tuning range of said one of said tunable circuits and effectively connected in circuit therewith to maintain said frequency difference more nearly constant.
- 10 17. In a high-frequency signaling system, a pair of circuits tunable to different frequencies and over different frequency ranges, means for simultaneously tuning said circuits over said ranges, reactance means included in one of said
- 15 circuits for maintaining the frequency difference of said circuits at a normal value only at predetermined frequencies within said ranges, and additional means comprising a third circuit resonant at one of said predetermined frequencies and
- 20 effectively connected in one of said pair of circuits for increasing the number of frequencies at which said frequency difference is at said normal value and for decreasing the departure of said frequency difference from said normal

value at frequencies above and below the resonant frequency of said third circuit.

18. In a high-frequency signaling system, a pair of tunable circuits each including an inductance and an adjustable condenser, said condensers being connected for unicontrol adjustment to tune said circuits over different frequency ranges with a frequency difference therebetween, reactance means included in one of said circuits for maintaining said frequency difference at a normal value only at predetermined frequencies within said ranges, and additional means comprising a third circuit resonant at one of said predetermined frequencies and including an inductance coupled to the inductance of 10 one of said pair of circuits for increasing the number of frequencies at which said frequency difference is at said normal value, the coupling between said coupled inductances being proportioned to decrease the departure of said frequency 15 difference from said normal value at frequencies above and below the resonant frequency of said third circuit.

HAROLD A. WHEELER.
